UNITED STATES PATENT OFFICE.

WILLIAM H. COX, OF MONTOURSVILLE, PENNSYLVANIA.

SKEWER-PIN MACHINE.

1,357,029.

Specification of Letters Patent.

Patented Oct. 26, 1920.

Application filed May 6, 1920. Serial No. 379,414.

To all whom it may concern:

Be it known that I, WILLIAM H. Cox, a citizen of the United States, residing at Montoursville, in the county of Lycoming and State of Pennsylvania, have invented 5 certain new and useful Improvements in Skewer-Pin Machines; and I do hereby declare the following to be a full, clear, and exact description of the invention, such as 10 will enable others skilled in the art to which it appertains to make and use the same.

The present invention relates to skewer- 15 pin making machines, and consists in the combination and arrangements of elements 20 hereinafter described and particularly set forth in the accompanying claims.

The invention has for its purpose to provide a machine of this character which will 25 form the skewer-pins from blanks by a series of coöperating sequential operations and without requiring any manual handling 30 of the pins from the time of the initial step to the completion of the final operation.

A further purpose of the invention re- 35 sides in providing a machine employing a feeding hopper, a scarfing knife, a series of pin forming dies, a conveyer adapted to receive the pins and block from the dies and carry the same and cutters for forming the 40 points of the pins individually as the same are conveyed, all operating in the sequence given and from a single power source.

The invention is disclosed by way of illustration in the accompanying drawings, 45 wherein—

Figure 1 is a top plan view of the machine;

Fig. 2, a side elevational view thereof;

Fig. 3, an end elevational view;

Fig. 4, a detail view of the scarfing knife;

Fig. 5, an end view of the die;

Fig. 6, a front elevational view of the die;

Fig. 7, a transverse sectional view taken 50 through the conveyer and showing the pin pointing apparatus sharpening device, and

Fig. 8 is a transverse sectional view of Fig. 7, taken on the line 8—8 thereof.

Referring to the construction in further detail, and wherein like reference characters 55 designate corresponding parts in the different views shown, the machine comprises a suitable supporting frame 9 adapted to be secured to a foundation by the apertured lugs 10, and 11 designates a hopper to receive the blanks B, that are adapted to be

delivered to the machine through the open hopper bottom 2 as shown (see Fig. 1). The blanks B are intermittently fed from the hopper by the reciprocable slide 13, that works in the groove 14 of the machine frame 60 9, and the operating means for the slide consists of a pitman 15 connected to the crank arm 16 of a crank shaft 17 (see Fig. 2).

In the forwarding operation from the hopper the blanks B are forced grain-wise 65 through the two scarfing knives 18, that are adjustably secured to the hopper frame 11 by the nut and bolt 19, and following the scarfing operation the blank is forced beneath a forwarding roller 20, whose journal 70 bearings 21 have limited play within the guides 22 formed in the posts 23 of the frame work 9. Said roller 20 has its pressure regulated by the hand adjusting wheels 24 and springs 25 (see Fig. 2).

A series of tubular dies 26 are located immediately adjacent the pressure roller 20 and in position to receive the scarfed blank as it issues from said roller, and said blank is forced through the several dies by the 75 feeding slide 13 acting on the next following blank to be delivered from the hopper as will be understood. The several tubular dies 26 are contained within the pair of clamping plates 27 and 28, which is in turn 80 bolted or otherwise secured to the frame 9, and each tubular die is formed with shoulder portions 29 and 30 giving a reduced intermediate portion, whereby the dies may be firmly secured between the clamping 85 plates 27 and 28 and be held against any slight displacement due to the pressure of the scarf blanks therethrough.

As each series of blanks or pins leaves the 90 series of dies under the force of the following blanks, it is delivered to the endless conveyer 31 (see Figs. 1 and 8) that is notched or grooved to receive said pins in proper spaced relation, as shown. Said conveyer belt is mounted on the pair of pulleys 32 and 33, and movement is imparted thereto by the chain and sprocket drive 34 and 35 (see Figs. 2 and 3). The chain 34 is driven from the sprocket 36 on the shaft 37, and said shaft is in turn driven from the power shaft 100 38 by the chain 39, and sprockets 40 and 41 mounted on said shafts 38 and 37, respectively.

The apparatus for forming the points P, on the pins S consists of two pairs of 105

knurled heads or rollers 42 and 43 that are located on either side of the conveyer belt 31 in such a manner that the pins are individually lifted out of their grooves in the belt (as shown in Figs. 7 and 8), and brought into contact with the rotary cutter 44, that is secured to and operates on the shaft 45, which is connected to be driven from the shaft 38 by the high-speed chain 10 and sprocket gearing 46, 47 and 48. It will thus be seen that by the action of the knurled heads 42 and 43, the blanks will each have imparted thereto a rotary motion about its own axis, and by the cutter roller 44 will thus have the point P symmetrically formed thereon. After this pointing operation each blank or pin as formed will be dropped into its proper notch or groove of the conveyer belt and thence carried to the 20 discharge end of the machine and deposited into a suitable receptacle thereat.

It will be seen from the foregoing that the several elements of the machine will be operated from a single power source connected 25 to drive the shaft 38, to wit: the shaft 17 is connected to be driven from said shaft 38 by the countershaft 49 through miter gears 50, 51, and 52, 53; the conveyer belt through the transmissions 34, and 35; the knurled heads 42 and 43 through the gearing 39 and 40, and the rotary cutter through the feed drive 46, 47 and 48.

It is obvious that those skilled in the art may vary the details of construction and 35 arrangement of parts without departing from the spirit of my invention, therefore I do not wish to be limited to such figures except as may be required by the claims.

Having thus described my invention, what 40 I claim as new and desire to secure by Letters Patent is:

1. In an apparatus of the character described, the combination of means for feeding a wooden blank, a scarfing knife for initially forming the articles from the wooden blank, a die for operating on the scarfed blank for forming the same into the separate articles, means for conveying the separate articles, and means for finishing the articles 50 singly, substantially as set forth.

2. In a machine for making skewer-pins, the combination of a supporting structure, a hopper adapted to receive the blanks, a scarfing knife adapted to initially form the pins from blanks, means for feeding the blanks to the scarfing knife, dies for receiving the blank from the scarfing knife and separating the same into the individual pin pieces, a conveyer adapted to receive said pieces from the dies, co-acting devices adapted to receive and separately hold the pin members, and a cutter adapted to point the blanks while held by said members, substantially as set forth.

3. In a machine for making skewer pins,

the combination of a suitable support, a hopper adapted to receive the blanks, a scarfing knife constructed to cut and initially form the blanks, a presser roller located in the rear of the scarfing knife, means 70 for feeding the blank through said scarfing knife and presser roller to initially shape the pins from the blank, a plurality of die members adapted to receive the blank from the presser roller and form the same into the 75 individual pin members, a conveyer adapted to receive the pin members from said dies, a pair of co-acting devices adapted to hold the blank pin members from the conveyer, and a cutter adapted to form the points on 80 the pins while the same are held by said co-acting members, substantially as set forth.

4. In a machine for making skewer pins, the combination of a suitable support, a hopper for holding blanks, a feeder operable 85 to deliver the blanks from the hopper, a scarfing knife for initially working the blanks as the same leave the hopper, a die for cutting the scarfed blank into the several pin members, a conveyer adapted to receive 90 the pin members from the die, a device for temporarily raising the pins from the conveyer and imparting rotation thereto, and a cutter for pointing the pins while the same are in raised position and rotated, substantially as set forth.

5. In a machine for making skewer pins, the combination of a suitable support, a hopper for holding blanks, a reciprocable feeder operable to deliver the blanks from 100 the hopper, a scarfing knife for initially cutting the blank in parallel rows as the same leaves the hopper, a plurality of tubular dies for cutting the scarfed blank into the several pin members, a conveyer adapted to receive the pin members in groups from 105 said tubular dies, co-acting rollers for temporarily and individually raising the pins from the conveyer and imparting rotation thereto, a rotary cutter for pointing the pins 110 while the same are in raised position and rotated, and a common actuating mechanism for said means, substantially as set forth.

6. In a skewer-pin making machine, the combination of a blank receiving hopper, a 115 scarfing knife for initially cutting the blank, dies for forming the scarfed blank into pin members, a reciprocable member for feeding the blanks from the hopper to the scarfing knife and said dies, a conveyer constructed 120 to receive the pin members in groups from said dies, rollers for temporarily raising and rotating the pin members from said conveyer, and cutters for forming points of said pin members while rotated by said rollers, 125 substantially as set forth.

7. In a skewer-pin making machine, the combination of a blank receiving hopper, a scarfing device for grooving the blanks, tubular dies for cutting the grooved blanks 130

into pin members, a reciprocable carrier for feeding the blanks from the hopper to the scarfing knife and said tubular dies, an endless conveyer having grooves adapted to separately receive the pin members from said dies, coöperable rollers adapted to separately lift said pin members from the conveyer and impart rotation thereto, a cutter for pointing the pin members during said rotation, and

a common operating means for said mechanisms, substantially as set forth.

In testimony whereof I affix my signature in the presence of two witnesses.
